SOUND RECORDING AND REPRODUCING SYSTEM

Orville M. Dunning, Glen Ridge, N. J., assignor to
 Thomas A. Edison, Incorporated, West Orange,
 N. J., a corporation of New Jersey

Application February 20, 1937, Serial No. 126,803

8 Claims. (CL 179—100.4)

This invention relates to sound recording and reproduction, and more particularly to systems arranged for the alternate performance of these two functions at will. It has especial, though not necessarily limitative, reference to recording and reproducing systems which involve the electrical amplification of the sound between the point of picking up (e. g., a microphone or phonographic pick-up) and the point of use (e. g., a phonographic recorder or loudspeaker).

In the use of systems of the type described for many purposes—prominent among which are the recordation and later reproduction of dictation, conferences or other speech—it is recognized as often desirable during recordation to reduce automatically volume contrasts which may actually exist in the sound as received by the microphone or the like, so that the recording means records upon the record sounds of very much more nearly uniform amplitude. This of course is principally because the volume range which can be satisfactorily recorded is usually rather limited, whereas the volume range of the sound to be recorded may be very wide—as when one person first speaks at small distance from a microphone, and then he or another speaks at many times that distance. Volume contrast-reducing or range-compressing means are therefore frequently employed in systems of the type described.

It is true, however, that such means are necessarily at least somewhat distorting in their effect upon the sound. I find that if effective such means are permitted to remain active during the functioning of the system for reproduction of sound as well as for the prior recordation of that sound, markedly unpleasant and highly inaccurate effects may be produced—in other words, the distortions which such means entail are "squared". And it is to be observed that their functioning during reproduction does not at all aid in meeting the initial requirement for their use in the system—the minimization of volume contrasts in the recording proper.

It is an object of my invention to provide a sound recording and reproducing system by which sounds of wide volume range may be satisfactorily recorded and reproduced with a minimum of distortion.

It is another object to provide a recording and reproducing system wherein volume contrasts are reduced only to a useful and not to a useless degree.

It is another object to provide a recording and reproducing system with an advantageous organization of portions and connecting means therefor, for fulfilling the broader objects of the invention.

It is another object to provide advantageous mutual arrangements of controlling means for a sound recording and reproducing system. It is

another object to provide a novel arrangement of recordation-reproduction converting means in a system for performing both those functions.

Still another object is to provide useful additional control means operating concomitantly with such converting means.

Still another object is to provide an improved volume range-compressing or contrast-reducing means, and control device therefor, for a sound recording system.

Other and allied objects will more fully appear from the following description and the appended claims.

In the description reference is had to the accompanying drawings, of which:

Figure 1 is a partly elevational and partly schematic view of a sound recording and reproducing system according to my invention, the apparatus being adjusted for recordation;

Figure 2 is a view of a portion of the apparatus of Figure 1, re-adjusted for reproduction; and

Figure 3 is a view of another portion of the apparatus of Figure 1, illustrating optional modifications thereof.

Reference being had to Figure 1, there will be seen a recording and reproducing phonograph designated generally as 1—purely by way of example, of the type arranged for reproduction by cutting upon wax records. The phonograph 1 may include for example the base 2, the right-hand end standard 3, the carriage rods 4a and 4b, and a carriage 5 slidable along those rods. Underneath the path of the carriage is seen a mandrel 6, journaled for example at the far (left-hand) end of the phonograph, and carrying a cylindrical record 7. It will be understood that in actual use the mandrel and record will be rotated, and the carriage meanwhile propelled slowly along the carriage rods, by means not herein necessary to show.

On the carriage over the record may be carried a recorder 14 and reproducer 13, in any desired arrangement relative to each other and to the carriage. The recorder and reproducer may have respective styli 12 and 11 (of which the former only appears in Figure 1), which may be selectively engaged with the surface of the record 7 by means of a control lever 8. This lever may extend upwardly from a suitable top aperture (not shown) in the carriage, and may move the styli (and simultaneously perform any other desired operations immediately upon the recorder and reproducer) through mechanism in the carriage not herein necessary to show. It may, however, be stated that the lever 8 is conveniently splined to the carriage rod 4a through the engagement of a key (not shown) on the lever with a key-way 4a' in the rod, so that as the lever is moved forwardly or rearwardly the rod 4a will be rotated.

Figure 1 shows the lever 8 in its most forward position, the rod 4a in its most counter-clockwise adjustment (as viewed from the right-hand phonograph end), and the recording stylus 12 engaging the record surface. Figure 2 solidly shows the lever 8 in its most rearward position, the rod 4a in its most clockwise adjustment, and the reproducing stylus 11 engaging the record surface. Dottedly Figure 2 shows the lever 8 in a mid or neutral position, it being understood that with this lever position both styli may be out of engagement with the record surface. The recorder and reproducer, and in particular their stylus means 12 and 11, will be understood to comprise record-cooperating translating means movable selectively by lever 8 into recording and reproducing relationships to the record.

The apparatus so far described with relation to the figures may be considered, for purposes of the present invention, as itself known; and in the same category may be placed a system of protective cams 9 and 10—these or equivalent means being frequently employed to prevent the removal of a record 1 from the mandrel 6 while either stylus is in engagement with the record surface. The cam 9 may be secured on the rod 4a, and may have the extending portion 9a disposed in the path of record removal when the lever 8 is adjusted (see Figure 2) for reproduction and the rod 4a is thus extreme clockwise. When the lever 8 is adjusted to neutral (dottedly shown in Figure 2) the cam 9 will occupy an intermediate position, dottedly shown, wherein its portion 9a no longer prevents record removal. As the lever 8 is adjusted for reproduction, however, the surface 9b of the cam 9 impinges on the surface 10b of the cam 10, which latter is pivoted below and slightly to the rear of the cam 9, and forces a clockwise rotation of the cam 10 to bring its extending portion 10a into the path of record removal.

The phonograph of Figure 1 is shown arranged to function for recordation with the microphone 15 as a pick-up device, and the amplifier 20 as a means of amplifying the output of the microphone for application to the recorder 14; further, it is shown arranged to function for reproduction with the loudspeaker 16, and the same amplifier 20 as a means of amplifying the output of the reproducer 13 for application to the loudspeaker. For recordation it is necessary to connect the microphone 15 to the amplifier input terminals 17, and to connect the amplifier output terminals 18 to the recorder 14; for reproduction it is necessary to connect the reproducer 13 to the amplifier input terminals 17, and to connect the amplifier output terminals 18 to the loudspeaker 16. The apparatus for switching or changing of these connections as required is simplified by the grounding—i. e., the connection to a common potential—of one electrical terminal each of the recorder 14, the reproducer 13, the microphone 15 and the loudspeaker 16, and of one of the amplifier input terminals 17 and of one of the amplifier output terminals 18; such terminal grounding has accordingly been shown in Figure 1, and the remaining terminal in each case may conveniently be designated as the "live" terminal.

I make the connection switching automatically responsive to stylus manipulation by lever 8; more specifically, to rotation of the carriage rod 4a; and still more specifically, to movement of the protective cam 10. To this end I may secure to the standard 3 a compound or multi-contact switch 22, having a member 22a of insulating

material disposed to be impinged on and moved by a surface 10c of the cam 10, for example only when the lever 8 is moved into recording position. The switch 22 may include pole members 27 and 28; contact members 25 and 24 respectively adapted to be contacted by those pole members when the lever 8 is in recording position (Figure 1); and contact members 23 and 26 respectively adapted to be contacted by those pole members when the lever 8 is not in recording (e. g., is in reproducing or neutral) position (Figure 2). All these members may be in the form of leaf springs clamped in the conventional insulating stack 22b, which may in turn be secured to the standard 3 by bracket 22c; the insulating member 22a above mentioned may be secured against the pole member 27; and the pole members may be tied together for movement in unison by insulating tie means 22d. The live terminals of recorder 14 and reproducer 13 may be connected by leads 34 and 33 respectively to contact members 24 and 23; the live terminals of microphone 15 and loudspeaker 16 may be connected by leads 35 and 36 respectively to contact members 25 and 26; and the live one of the input terminals 17 and the 25 live one of the output terminals 18 may be connected by leads 37 and 38 respectively to pole members 27 and 28. It will be seen that the switch structure and connections described in this paragraph meet the requirements set forth in the 30 preceding paragraph.

While in the practise of my invention the volume contrast-reducing or range-compressing means are not necessarily limited to association with an electrical amplifier, such an association 35 is a particularly convenient arrangement and has been illustrated herein. Accordingly the amplifier is provided with an "automatic volume control" circuit, which functions to regulate the amplifier gain approximately in inverse accordance with the volume applied to the amplifier input. In Figure 1, 20 represents a typical amplifier provided with a typical control circuit of the type just mentioned; it may now be described more in detail, it being understood, however, that the amplifier and volume control description is not to be taken as limitative. 45

The illustrated amplifier comprises three stages respectively employing the pentode tube 41 of the variable-mu or gradual bias cut-off type, the 50 similar pentode tube 42, and the two power output pentode tubes 43 in push-pull arrangement. The amplifier input terminals 17 are coupled to the grid of tube 41 by the input transformer 44 (with secondary loaded if desired by resistance 45) and condenser 46; the tube 41 is coupled to the grid of tube 42 by the coupling resistor 47 and the condenser 48; the tube 42 is coupled to the two tube 43 grids by the coupling resistor 49, the condenser 50, and the push-pull input auto-transformer 51; and the two tubes 43 are coupled to the amplifier output terminals 18 by the push-pull output transformer 52. The grid return for the two tubes 43 may be connected to the negative terminal of a battery or other high-potential current source 53, and the cathodes of those tubes may be biased above the potential of that terminal through a bias resistor 54. The supply of screen and plate potentials to the several tubes, which may be from various points on the source 53, has been indicated simply schematically by arrows. 60

The cathodes of tubes 41 and 42 may be connected together, and biased to a potential slightly higher than that of the negative source terminal 75

by connection to a suitable point **P** in the source 53; the magnitude of this biasing potential may equal a normal (full-gain) grid bias for these tubes. Grid leaks 55 and 56 are provided for the 5 respective tubes 41 and 42; and were these leaks returned simply to the negative source terminal, these tubes would always operate at full gain. The leaks are returned (through filters 57, 58, 59 10 hereinafter mentioned, and conductor 63) to that negative terminal, but this return also passes through a resistor 60—across which the automatic volume control circuit, next described, at times builds up a voltage to render the tube 41 and 42 grids extra-negative, and thus to reduce their 15 gain and thus that of the amplifier.

The automatic volume control circuit may be simply provided by placing on the output transformer 52 a tertiary winding 61, in which voltage is developed in proportion to that across the 20 output terminals, and connecting this in series with a rectifier 62 and the above mentioned resistor 60. The rectifier 62 is so poled that it passes current in the circuit 60—61—62 only in the direction of the arrow designated as 60a; this direction 25 will be seen to be such that any resulting voltage drop in resistor 60 will always be poled to render conductor 63 more negative than the negative terminal of source 53. Thus it will be understood that when substantial output voltages 30 appear across the output terminals 18 and hence across the tertiary winding 61, pulsating unidirectional current will flow in the circuit 60—61—62, and a pulsating extra-negative potential (relative to the negative source terminal) 35 will appear on the conductor 63. This potential is passed to the grid leaks of the tubes 41 and 42 through the resistance-condenser filter 59 (59a—59b); additionally as to tube 42, through the resistance-condenser filter 58 (58a—58b); 40 and additionally as to tube 41, through the two-stage resistance-condenser filter 57 (57a—57b, and 57c—57d). These filters substantially eliminate the pulsations from the extra-negative potential in question; and the net results are the 45 applications to the grids of tubes 41 and 42 of a substantially smooth extra-negative bias, and a reduction of their and the amplifier gain, of degree responsive to the amplifier output voltage. By employment of a sufficiently large tertiary winding 61, the amplitude of the extra-negative bias may be made high enough so that 50 for a very wide range of input voltage (across 17) the amplifier gain will vary almost inversely as that input voltage, and the output voltage (across 18) will vary only slightly. So the volume contrast-reduction or range-restriction is effected.

It may here be mentioned that this contrast-reduction or range-restriction may broadly be 55 described as a modification (e. g., reduction) of the ratio of output to input energies of the common system portion (e. g., the amplifier).

It may be noted that the resistance-condenser filters 57, 58 and 59 must provide a sufficient 60 attenuation of low as well as other frequency components to avoid self-oscillation of the amplifier through feed-back, and must at the same time not be so unreasonably large in respect of individual series resistance and shunt capacity 65 as to result in undue time delay in the operation of the automatic volume control—the arrangement of the filters as a plurality of sections being a convenient means to the joint attainment of these ends.

75 The connection from the rectifier 62 to the re-

sistor 60 has been shown as made through a small portion of the source 53—i. e., to a point **P'** of slight positive potential in that source. This is desirably done so that relatively weak input and output voltage will not cause the development 5 of any extra-negative bias or any amplifier gain reduction—in other words, so that no volume control action is produced with very weak input voltages which, being for example appreciably below the optimum recording level, should at least 10 be recorded with that full amplitude which they actually do possess. This result is secured because the inclusion of the small steady potential in the circuit 60—61—62, of polarity tending to render the cathode of the rectifier more positive 15 than the anode, prevents any current flow in that circuit until the peak voltage from 61 has risen above a threshold value represented by the steady potential in question.

To avoid the extra and useless distortion which 20 would result from the use of the automatic volume control action in reproduction I provide means, responsive to a reproducing adjustment of the phonograph system, for eliminating that action. I have shown this means, more specifically, 25 responsive to a reproducing position of lever 8 or rod 4a; and still more specifically, to a reproducing position of switch 22. Most conveniently such responsiveness is secured by including in that switch an additional pole member 29 and 30 an additional contact member 30, appropriately associated electrically with the automatic volume control circuit. In the case of the particular circuit 60—61—62 which has been illustrated, elimination of automatic volume control action 35 is most conveniently secured by simple open-circuiting. So that circuit has been made serially to include the contacts or terminals 19, connected by leads 39 and 40 to the switch members 29 and 30 just above mentioned; and those switch members 40 have been arranged to be closed against each other, completing the circuit, when the phonograph system is adjusted (as in Figure 1) for recordation, and to be out of contact with each other, opening the circuit, when the system is adjusted (as in Figure 2) for reproduction 45 (and, if desired and as illustrated, when adjusted in "neutral"). It is of course to be understood, however, that there is intended no limitation to the details of the arrangement which 50 has been shown, for selectively providing and eliminating the volume contrast-reducing or range-compressing (e. g., automatic volume control) action, as such details will naturally be varied in accordance with the particular means 55 employed for producing that action in any given case.

Figures 1 and 2 have contemplated the use of separate recorder and reproducer, and the use of separate microphone and loudspeaker (or its 60 equivalent, an earphone or the like). The recorder and reproducer may, however, be combined into a single unit with or without distinct stylus; or the loudspeaker and microphone may be combined into a single unit. Both such combinations have been illustrated in Figure 3, wherein a combined recorder-reproducer appears as 134, and a combined microphone-loudspeaker (or microphone-earphone) as 156. The first such combination permits the merging of the 65 leads 33 and 34 of Figure 1 into a single lead 334 connecting with both contact members 23 and 24; the second permits the merging of leads 35 and 36 into a single lead 356 connecting with both contact members 25 and 26 (which may ob- 70 75

viously then themselves be merged if desired); and both of such mergings of leads have accordingly been illustrated in Figure 3.

While in Figures 1 and 2 I have shown the modification of automatic volume control action, occurring upon change from recordation to reproduction, as an infinite one (i. e., the reduction of that action to a zero value), my invention broadly embraces any modification of that action. So in Figure 3 I have schematically indicated the optional inclusion of a resistor 64 across the leads 39 and 40, and thus across the automatic volume control circuit contacts or terminals 19. This obviates full opening of the automatic volume control circuit during reproduction, and instead causes a finitely reduced volume control action then to obtain, in view of a division of rectified voltage between the active resistor 60 and the passive resistor 64, in substantial proportion to their values.

It will of course be understood that while I have shown an arrangement whereby the automatic volume control action is eliminated with the control lever 8 in "neutral" as well as in reproducing position, the matter of whether it is or is not eliminated in the "neutral" adjustment is ordinarily immaterial. It is further to be understood that while I have shown the switching means as manipulated immediately at the phonograph 1 (e. g., by lever 8), my disclosure is obviously likewise adapted for use with remote or remotely controlled switching. Further, I may call attention to the simplicity of the arrangement—a single-pole, single-throw switch (29—30) across the serial contacts or terminals 19—for including or eliminating the automatic volume control action, which I believe to be of utility in itself, independently of association with the recording-reproducing switching means.

Finally it will be understood that while I have disclosed my invention in terms of specific embodiments thereof, I do not intend that its scope be limited by the details of those embodiments; rather I intend in the appended claims to set forth its scope as broadly as the state of the art will permit.

I claim:

1. In a phonograph system selectively adapted for the recordation and reproduction of sound: the combination of a record support; record-cooperating translating means; selective control means for moving said translating means selectively into recording and reproducing relationships to a record on said support; means for effecting a compression of the volume range of said sound; and means, controlled by said selective control means, for controlling said compression-effecting means.

2. In a phonograph system selectively adapted for the recordation and reproduction of sound: the combination of a record support; record-cooperating translating means; selective control means for moving said translating means selectively into recording and reproducing relationships to a record on said support; means for effecting a reduction of volume contrasts in said sound; and means, controlled by said selective control means, for controlling said reduction-effecting means.

3. In a phonograph system selectively adapted for the recordation and reproduction of sound: the combination of a record support; record-cooperating translating means; selective control means, movable to recordation and reproduction positions, for moving said translating means se-

lectively into recording and reproducing relationships to a record on said support; means for effecting a compression of the volume range of said sound; and means, rendered effective by said selective control means when in reproduction position, for eliminating said compression.

4. In a phonograph including a record support: the combination of record-cooperating translating means; selective control means for moving said translating means selectively into recording and reproducing relationships to a record on said support; an electrical amplifier feeding said translating means during recordation and fed by said translating means during reproduction; automatic volume control means associated with said amplifier; and means, controlled by said selective control means, for controlling said automatic volume control means.

5. In a phonograph including a record support: the combination of record-cooperating translating means; selective control means for moving said translating means selectively into recording and reproducing relationships to a record on said support; an electrical amplifier feeding said translating means during recordation and fed by said translating means during reproduction; means associated with said amplifier for modifying the relationship between input and output energies thereto and therefrom; and means, controlled by said selective control means, for controlling said modifying means.

6. In a phonograph including a record support: the combination of record-cooperating translating means; selective control means, movable to recordation and reproduction positions, for moving said translating means selectively into recording and reproducing relationships to a record on said support; an electrical amplifier feeding said translating means during recordation and fed by said translating means during reproduction; automatic volume control means associated with said amplifier; and means, rendered effective by said selective control means when in reproduction position, for placing said automatic volume control means out of operation.

7. In a phonograph system selectively adapted for the recordation and reproduction of sound: the combination of a record support; record-cooperating translating means movable selectively into recording and reproducing relationships to a record on said support; protective means, moved incidentally to the movement of said translating means, for preventing the removal of a record from said support; an electrical amplifier feeding said translating means during recordation and fed by said translating means during reproduction; volume compressing means associated with said amplifier; and means, associated with and responsive to the position of said protective means, for controlling said compressing means.

8. In a phonograph system for both sound recordation and sound reproduction, including a record support and record-coating recording and reproducing means: selective means for adjusting said record-coating means for sound recordation and sound reproduction; protective means responsive to said selective means for preventing the removal of a record from said support; an electrical amplifier; electro-acoustic translating means; and switch means, associated with and operated by said protective means, for variously associating said record-coating means and said electro-acoustic translating means with said amplifier.
